M. S. BASSETT.

Sifting and Bolting Flour, &c.

No. 11,822.

Patented Oct. 24, 1854.

UNITED STATES PATENT OFFICE.

MARK S. BASSETT, OF WILMINGTON, DELAWARE.

SIFTING AND BOLTING.

Specification of Letters Patent No. 11,822, dated October 24, 1854.

To all whom it may concern:

Be it known that I, MARK S. BASSETT, of the city of Wilmington, in the county of New Castle and State of Delaware, have invented a new and useful Improvement for Sifting and Reducing the Lumps in Flour and other Siftable Substances; and I do hereby declare that the following is a full, clear, and exact description of the same, reference being had to the annexed drawings, making a part of this specification, in which—

Figure 1 is a vertical middle section. Fig. 2 is the rotating riddle or what I term the feeder, distributer, and vibrator. Fig. 3 is a stationary sieve disk and hoop.

My improvement is intended to be used for sifting flour, meal, and other substances and for reducing the lumps usually contained therein. The usual method of sifting flour, molding sand, guano, drugs, &c., is with the ordinary hand sieve, which is a tedious and unpleasant operation, requiring a secondary resort to pounders or crushers to reduce the lumps. Where large quantities are to be sifted the mill is resorted to, where it is first ground over, as it is termed, then elevated and bolted. To facilitate this labor and avoid a complication of machinery, I have contrived a feeder, distributer, and vibrator in connection with an ordinary sieve; may be used by hand or power. It may be arranged in a hopper or spout leading to a bolt in place of the ordinary shoe for the purpose of regularly feeding and relieving said bolt from the clots and lumps.

To make my improvement I take a common hand sieve or its equivalent, a vertical middle section of which is shown in Fig. 1 having a deep upper band or hoop L forming a hopper or receiver to sieve M, although other forms may be used for the framework of the sieve. In and across said hopper I firmly fasten two bars A, A. Said bars should be of sufficient distance apart to form two distinct bearings through which I pass a shaft B firmly connecting the lower end thereof to a transverse bar C, Fig. 2.

Fig. 2 represents the feeder, distributer, and vibrator; is made circular of coarser web than the sieve, having a metal margin or rim made flat and slightly rough underneath. The use of said rim is to confine the web G within its circle, E, E, and also to form a bearing when in contact with the sieve. The cross bar C is slightly arched up-

ward and firmly riveted at each end to the rim E. Said bar has two thumb screws F, F, Figs. 1 and 2, passing through it, one on each side of the shaft and connecting with the web directly under them by a swivel plate. Their use is to adjust the said web so that it shall not come in contact with the sieve or bolting disk except at its margin or bearings, thereby preventing excess of friction, and also to form a space between said distributer and sieve sufficient for the particles of siftable matter to circulate freely from the center of the sieve's disk toward the periphery, without grinding or forcing them into the meshes. This arrangement will appear more obvious when taken into consideration that the particles too coarse to pass the lower sieve and being confined by the mass within the meshes of the distributer and against the sieve would have no means of escape, hence the necessity of a slight separation as above described.

Fig. 3 is the lower hoop with the web attached of an ordinary hand sieve, letter M, Fig. 1. Around the margin of said sieve disk and within the hoop is a metal rim D, D made flat and corresponding with one in Fig. 2, letters E, E, Fig. 2, is firmly fastened to the shaft B, and passed through the two bars A, A, across the hopper, Fig. 1, centralizing Fig. 2 directly over the sieve M, Figs. 1 and 3, and in contact at the corresponding bearings E, E, and D, D, Figs. 1, 2, 3.

First operation: The riddle rotating over and in contact with the sieve partially relieves said sieve from the mass of siftable matter contained in the hopper above it, gradually grating said mass through the meshes, feeding and reducing the lumps; second, a centrifugal motion produced by the action of the square meshes on the particles while passing through them, this action being centrifugal so far as the meshes alone are concerned; the general action is outward or toward the periphery or distributing; third, the vibration produced by a slight roughness at the bearings together with the constant changing of the particles adjacent to and between the sieves toward the periphery effects an open current for the finer particles to pass the sieve and without a probability of clogging or choking.

The machine above described is only claimed as an improvement upon one for which I obtained a patent, dated June 20th,

1854. The patent, if obtained, will be subordinate to that patent, and can only be used with the license and permission of the holder of the former patent.

5 I do not claim the hopper, the flat sieve or rotating riddle alone nor the shaft and bars as above arranged and described; but

What I do claim as my invention and desire to secure by Letters Patent is—

10 The riddle as arranged and described in

Fig. 2, in connection with a shaft and bearings centralizing said riddle so as to rotate against an ordinary flat sieve disk at its margin as a feeder, distributor, and vibrator, combined for the uses and purposes herein set forth. 15

MARK S. BASSETT.
